SAFETY RAZOR AND PROTECTIVE CASING

Evelyn M. Biggs, Pawtucket, R. I.

Application December 7, 1948, Serial No. 63,876

5 Claims. (Cl. 30—47)

1

This invention relates to a safety razor and protective casing therefor.

An object of the invention is the provision of a safety razor formed of inexpensive materials so that it may be discarded after a single shave, the usual blade being protected by a casing during storage or transportation, said casing being foldable to form the supporting handle of the blade.

A further object of the invention is the provision of an inexpensive razor to be supplied to travelers in an emergency and to be discarded after it has been used once or twice, the usual blade forming a permanent fixture of the shaving implement which may be constructed of cardboard, reinforced if necessary with a cheap metal, the implement including a protective casing for the blade having sufficient dimensions to house a small tube of shaving cream and the blade while being foldable to form a handle of the razor.

Other objects and advantages will become apparent from a consideration of the following description and the appended claims in conjunction with the accompanying drawings wherein:

Figure 1 is a plan view of the razor and protective casing in unfolded condition;

Figure 2 is a side or edge elevational view of the structure illustrated in Figure 1;

Figure 3 is a front elevational view of the structure when folded to provide a protective casing or container;

Figure 4 is a rear elevational view of the structure in the condition illustrated in Figure 3;

Figure 5 is a side elevational view of the structure in the condition illustrated in Figures 3 and 4;

Figure 6 is a cross sectional view on the line 6—6 of Figure 3;

Figure 7 is a cross sectional view on the line 7—7 of Figure 6;

Figure 8 is a cross sectional view on the line 8—8 of Figure 6;

Figure 9 is a side or edge elevational view of the structure when partly folded to provide a safety razor;

Figure 10 is a rear elevational view of the structure when completely folded to provide a safety razor;

Figure 11 is a side or edge elevational view of the structure when in the condition illustrated in Figure 10;

Figure 12 is a front elevational view of the structure when in the condition illustrated in Figure 10;

2

Figure 13 is a perspective view of the structure when in the condition illustrated in Figure 10;

Figure 14 is a perspective view of a channel bar constituting an operative component of the device; and

Figure 15 is a side elevational view on an enlarged scale of a fragmentary upper portion of a somewhat modified form of the structure.

With continued reference to the drawings, the numeral 10 generally designates a blank, as illustrated in Figure 1, formed of a foldable sheet material, such as lightweight cardboard. This blank is of elongated rectangular shape with wings 11 and 12 of elongated rectangular shape 15 extending one from each side of blank 10 near one end thereof and is divided by transversely extending and substantially parallel fold lines 13, 14, 15, 16 and 17 into six sections, as indicated at 18, 19, 20, 21, 22 and 23 extending from one end of the blank to the other end thereof in end to end relationship in the order indicated.

The sections 19 and 21 are of substantially the same length and constitute the front and back walls of a rectangular receptacle formed from the blank in a manner to be later described. The sections 20 and 22, respectively disposed between sections 19 and 21 and sections 21 and 23, are of substantially the same length, but shorter than the sections 19 and 21, and constitute the ends of the receptacle formed from the blank.

The wings 11 and 12 extend along the corresponding sides of section 19 between fold lines 13 and 14, so that section 18 is disposed entirely beyond the adjacent ends of the wings and the wing 11 is divided by a score or fold line 24 spaced from and substantially parallel to the adjacent side edge of section 19 into two sections 25 and 26. The wing 12 is divided by a score or fold line 27 spaced from and substantially parallel to the corresponding side edge of section 19 into two sections 28 and 29.

The wing sections 25 and 28 adjacent section 19 have a width substantially the same as the length of sections 20 and 22 and constitute the sides of the receptacle formed from the blank. The wing sections 26 and 29 have a width materially less than the width of sections 25 and 28 and constitute supporting tabs for the front wall of the receptacle when the receptacle is formed.

The end section 18 has a length substantially the same as the width of a commercial safety razor blade and constitutes a blade support. A safety razor blade 30 is superimposed on one side of the blade support section 18 with its cutting edge disposed slightly beyond the end of this sec-

tion and is secured to the blade supporting section as by being glued or cemented thereto.

The blank is bent along the fold line 13, so that the section 18 is disposed at an acute angle to the section 19 with the blade on the outer side of the blade support section 18.

The blade 30 and blade support section 18 are provided with apertures 31 and 32 disposed intermediate the width of the blade and one near each end thereof and strips 33 and 34 of thin sheet metal, such as sheet aluminum, extend through the apertures 31 and 32 respectively and have bent over outer portions 35 and 36 superposed on the outer surface of the blade 30 and cemented thereto. At their other ends the strips 33 and 34 have bent over end portions superimposed upon and cemented to the adjacent surface of blank section 19 at locations spaced from the fold line 13, so that these strips support the blade and blade support blank section at a predetermined acute angle relative to section 19.

An elongated sheet metal bar 37 of channel shaped cross section is secured on the blade 30 along the edge of the blade remote from the sharpened edge thereof and receives this edge portion of the blade and adjacent end portion of section 19 therein, the bar being cemented to the blade and the portion of the blank along the fold line 13 to reinforce the connection between the blade and the blank.

The end section 23 of the blank remote from the blade support section 18 is longer than the sections 20 and 22, but shorter than the sections 19 and 21 and is used to constitute a portion of a handle formed by collapsing the receptacle in a manner later to be described after the receptacle has been formed from the blank 20.

Tabs 38 and 39 of rectangular shape and formed of bendable sheet material, such as sheet aluminum, are secured each at one end thereof to the blank section 21 substantially at the mid-length location of each side margin of this section and extend outwardly one from each said side margin of the section 21.

Tabs 40, 41, 42 and 43, of rectangular shape, are secured to section 23, one at each corner thereof at the same side of the blank as that at which the tabs 38 and 39 are secured and extend outwardly from the side edges of section 23 one at each end of each side edge.

Forming the blank into a receptacle

In order to provide a receptacle to enclose the blade 30, the blank is first bent at right angles along fold lines 44 and 45 along which the wings 11 and 12 are respectively joined to the section 19, then along the fold lines 24 and 27. This places sections 25 and 28 forming the side walls of the receptacle perpendicular to the section 19 and the sections 26 and 29 forming the reinforcing tabs perpendicular to the sections 25 and 28 and extending inwardly from the edges of these sections remote from the section 19 constituting the back wall of the receptacle. The blank is then successively bent at right angles along the fold lines 14, 15, 16 and 17, first placing the end forming section 20 perpendicular to the back forming section 19 with its ends contiguous to the corresponding ends of the side forming sections 25 and 28, then disposing the front forming section 21 perpendicular to the end forming section 20 and superimposed on the supporting tabs 26 and 29 and spaced from and substantially parallel to the back forming section 19. The other end forming section 22 is then disposed perpendicular

to the back and front forming sections 19 and 21 with its ends contiguous to the adjacent ends of the side forming sections 25 and 28 and overlying the blade 30 and bar 37. The section 23 is then lapped over the outer side of the back forming section 19 and the tabs 40, 41, 42 and 43 are bent at right angles to the section 23 along the side edges of section 23 and inserted through corresponding slots 46, 47, 48 and 49 provided in the blank at spaced apart locations along the fold lines 44 and 45. The tabs 38 and 39 are now bent at right angles to section 21 along the corresponding edges of the section 21 and again bent at right angles along the corresponding edges of the section 23 to provide at their distal end portions, as indicated at 50 and 51 in Figure 4, overlying the outer surface of the section 23 to hold the receptacle in shape.

This provides a receptacle of rectangular shape as illustrated in Figures 3 to 8 inclusive, which encloses the blade 30 and may contain a tube 52 of shaving cream, as shown in Figures 6 and 8.

Forming razor handle from receptacle

In order to form a razor handle from the rectangular receptacle, as described above, the tabs 38 and 39 are first straightened at the inner ends of the end portions 50 and 51 and the tabs 40, 41, 42 and 43 are withdrawn from the slots 46, 47, 48 and 49, freeing the section 23. The sections 23, 22 and 21 are then turned back away from sections 19, 25 and 28. The wings 11 and 12 are then straightened along the fold lines 24 and 27 and folded back along the fold lines 44 and 45 until they are superposed on the side of the section 19 remote from the blade 30. The blank is then straightened along the fold lines 14 and 16 and folded along the fold line 15, so that section 21 overlaps section 20 and sections 21 and 22 are superposed on the sides of the wings 11 and 12 remote from the section 19. The blank is then folded along fold line 17, so that section 23 is superposed on the sides of sections 21 and 22 remote from the wings 11 and 12 and tabs 40, 41, 42 and 43 are then reinserted through slots 46, 47, 48 and 49 respectively. Tabs 38 and 39 are then bent around the edges of the folded blank, so that the distal end portions 50 and 51 are disposed against the side of section 19 adjacent the blade 30.

This arrangement provides a compact handle, as illustrated in Figures 10, 11, 12 and 13, of sufficient stiffness for use in shaving.

In the modified arrangement shown in Figure 15, the blade support section 18 comprises a blank portion longer than the width of the blade and is folded upon itself to provide two superposed layers 53 and 54 underlying the blade 30, and a third layer 55 overlying the outer side of the blade. The strips 33 and 34 extend through the three layers 53, 54 and 55 of the blade support, as well as through the blade itself, and the bent over outer end portions of these strips are superposed on and cemented to the outer surface of the outer layer 55.

This is a disposable razor and if, after it has been used once for shaving, it is not returned to its receptacle form, but is merely discarded.

The invention may be embodied in other specific forms without departing from the spirit or essential characteristics thereof. The present embodiments are, therefore, to be considered in all respects as illustrative and not restrictive, the scope of the invention being indicated by the appended claims rather than by the foregoing

description, and all changes which come within the meaning and range of equivalency of the claims are, therefore, intended to be embraced therein.

What I claim:

1. A disposable safety razor comprising an elongated rectangular body of foldable sheet material having transversely disposed fold lines dividing it longitudinally into six consecutively arranged sections and longitudinally disposed fold lines dividing it transversely at one end into three contiguous sections of which the center section is one of said six consecutively arranged sections, means supporting one terminal section of said six contiguous sections at an acute angle to the section adjacent thereto, a razor blade carried by said one terminal section, tabs on an intermediate one of said six consecutively arranged sections engageable with the other terminal section to hold said sections in that one of two folded conditions in which they constitute a container inclosing said razor blade, and tabs on the other terminal section of said six consecutively arranged sections engageable in slots between said center section and side sections of said three contiguous sections to hold said sections in the other of said two folded conditions in which they constitute a blade handle extending from one edge of said one terminal section.

2. An assembly comprising an elongated body of foldable sheet material foldable along transversely and longitudinally extending lines to provide a plurality of contiguous sections foldable relative to each other, a razor blade secured to the section at one end of said body, means holding the blade carrying section at an acute angle to the section adjacent thereto and overlying a portion of such adjacent section, and means carried by the section at the other end of said body and engageable with other of said sections to hold said sections in either of two alternative folded conditions in one of which they provide a container enclosing said blade and in the other of which they provide a handle extending from one edge of said blade carrying section.

3. An assembly comprising an elongated body of foldable sheet material foldable along transversely and longitudinally extending lines to provide a plurality of contiguous sections foldable relative to each other, a razor blade secured to the section at one end of said body, means holding the blade carrying section at an acute angle to the section adjacent thereto and overlying a portion of such adjacent section, means carried by the sections to hold said sections in either of two alternative folded conditions in one of which they provide a container enclosing said

blade and in the other of which they provide a handle extending from one edge of said blade carrying section, and a channel-shaped stiffener clamped upon said blade at one edge of the latter and upon said blade carrying section and said adjacent section.

4. An assembly comprising an elongated body of foldable sheet material foldable along transversely and longitudinally extending lines to provide a plurality of contiguous sections foldable relative to each other, a razor blade secured to the section at one end of said body, means holding the blade carrying section at an acute angle to the section adjacent thereto and overlying a portion of such adjacent section, means carried by the section at the other end of said body and engageable with one of the other sections to hold said sections in either of two alternative folded conditions in one of which they provide a container enclosing said blade and in the other of which they provide a handle extending from one edge of said blade carrying section, and bendable elements carried by an intermediate section and engaging another of said sections when said sections are folded relative to each other to provide the blade enclosing retainer for releasably securing said sections in such folded condition.

5. An assembly comprising an elongated body of foldable sheet material foldable along transversely and longitudinally extending lines to provide a plurality of contiguous sections foldable relative to each other, a razor blade secured to the section at one end of said body, means holding the blade carrying section at an acute angle to the section adjacent thereto and overlying a portion of such adjacent section, means carried by the section at the other end of said body and engageable with one of the other sections to hold said sections in either of two alternative folded conditions in one of which they provide a container enclosing said blade and in the other of which they provide a handle extending from one edge of said blade carrying section, said blade carrying section being folded to provide a blade holder having a portion overlying and a doubled portion underlying the blade.
